SHOWCASE LOCK

Edmund J. Gapinski, New York, N. Y.

Application February 8, 1939, Serial No. 255,333

2 Claims. (Cl. 70—14)

This invention aims to provide a simple mechanism whereby slidable panels, such as those used in show cases, may be held together, against opening movement.

5 It is within the province of the disclosure to improve generally and to enhance the utility of devices of that type to which the present invention appertains.

With the above and other objects in view, which 10 will appear as the description proceeds, the invention resides in the combination and arrangement of parts and in the details of construction hereinafter described and claimed, it being understood that changes in the precise embodiment 15 of the invention herein disclosed, may be made within the scope of what is claimed, without departing from the spirit of the invention.

In the drawing:

Fig. 1 shows in elevation, a device constructed 20 in accordance with the invention, assembled with the slidable panels of a show case;

Fig. 2 is a sectional view wherein the device forming the subject matter of this application is shown in top plan;

25 Fig. 3 is a section taken through the lock;

Fig. 4 is a rear elevation of the lock, parts being broken away;

Fig. 5 is a plan of the lock as it appears before being adapted to use.

30 In carrying out the invention, there is provided a lock case 1, wherein a barrel 2 is mounted to turn, the barrel being rotated by a key 3, the tumbler mechanism 4 being of common form. On one end of the barrel 2 there is an outstanding flange 5. On the opposite end of the barrel 2, a disk-like head 6 is held by securing elements 7. The head 6 and the flange 5, cooperating with the lock body 1, hold the barrel 2 against endwise movement in the lock body. The head 6 has 35 a hub 8 to which a rigid, laterally projecting latch strip 9 is attached by a securing element 10.

The lock case 1 is supplied with a rearwardly projecting offset 11, in which an arm 12 is secured at one end, the arm and the latch strip 9 being located in the same plane. The arm 12 terminates in a rectangularly disposed finger 14.

45 The numeral 15 marks a show case frame, wherein panels 16 and 17, generally made of glass, are slidably mounted.

50 In practical operation, by means of the key 3,

the barrel 2 is rotated until the latch strip 9 is disposed at right angles to the arm 12. The device is rotated about an axis represented by the arm 12, until the finger 14 is parallel to the panels 16 and 17. The arm 12 is inserted between the 5 panels 17—16, and the entire device is rotated to the position of Fig. 2, about an axis represented by the arm 12, the finger 14 engaging the edge of the panel 16. Then, by means of the key 3 the barrel 2 is rotated, the latch strip 9 swinging 10 down between the panels 16 and 17, as in Fig. 2, and it being impossible, then, to rotate the device about an axis represented by the arm 12 and disengage the finger 14 from the edge of the 15 panel 16.

It is to be observed that the locking mechanism is used only to swing the latch strip 9. The arm 12 is rigid and is secured in the offset 11 of the casing 1, and no locking mechanism is provided for rotating the arm 12 to engage the finger 20 14 with the edge of the panel 16.

Referring to Fig. 5, the arm 12 is straight, as shown at 18, as it comes from the manufacturer. The user inserts the straight arm 18 between the panels 16 and 17, bends the straight arm 18 to 25 form the finger 14, as may be required in a particular show case, and then cuts off the finger 14 to the desired length.

What is claimed is:

1. An article of manufacture for use in the 30 making of a show case lock, and comprising a lock body, a rotatable member carried by the body, a latch secured to the rotatable member and disposed substantially at right angles to the axis of rotation of said member, and a straight, rigid 35 arm fixedly secured to the body and disposed substantially in a common plane with the latch, the arm being bendable at the will of an operator, to form a finger disposed at an angle to the arm, and to determine the length of the arm. 40

2. A show case lock comprising a lock body, a rotatable member carried by the body, a latch secured to the rotatable member and disposed substantially at right angles to the axis of rotation of said member, and an arm fixedly secured to the 45 body and disposed substantially in a common plane with the latch, the arm being provided with an angularly disposed finger.
